UNITED STATES PATENT OFFICE.

ALFRED W. ROOVERS AND ALEXANDER H. ROOVERS, OF BROOKLYN, NEW YORK.

COIN-OPERATED POWER OR STRENGTH TESTING MACHINE.

SPECIFICATION forming part of Letters Patent No. 423,702, dated March 18, 1890.

Application filed June 14, 1889. Serial No. 314,212. (No model.)

To all whom it may concern:

Be it known that we, ALFRED W. ROOVERS and ALEXANDER H. ROOVERS, both citizens of the United States, residing at Brooklyn, in 5 the county of Kings and State of New York, have invented a certain new and useful Improvement in Coin-Operated Power-Testing Machines, of which the following is a specification.

10 This machine relates more particularly to that class of machines in which the striking or kicking power of a person may be determined or registered; and it consists in the novel arrangement and construction of parts, 15 as hereinafter set forth.

In the drawings, Figure 1 is a perspective view of the mechanism embodying my improvement with certain parts broken away to save space, and Fig. 2 is a side view of the 20 same.

Similar letters of reference indicate like parts in both figures of the drawings.

Referring by letter to the drawings, A designates a main shaft, (here shown as having 25 bearings in the hangers a,) which may depend from the casing of the machine, (not shown;) or this shaft may have its ends journaled in the front and rear wall of the casing.

B designates a disk or dial mounted friction-tight on the shaft A adjacent to the 30 front wall a', which has a small opening a' in line with a circular row of figures or characters on the face of the dial B.

B' is a ratchet-wheel rigidly secured to the 35 shaft A in the rear of the dial, and B² is a similar ratchet-wheel, but somewhat smaller in circumference than the wheel B', also rigidly attached to the shaft A near its opposite end. These wheels B' B², it will be observed, 40 Fig. 1, have their teeth oppositely arranged.

In the rear of the ratchet-wheel B' is a toothed or gear wheel C, which is loosely mounted on the shaft A, so as to turn independently of the shaft. In order that this 45 wheel C may not turn too freely on the shaft, we provide a friction-bearing, (here shown as a spring c,) arranged in the collar c' of the wheel C. Another gear-wheel C' is loosely mounted on the shaft A at one side of the 50 ratchet-wheel B². This wheel C' is smaller than the wheel C. The relative sizes of these

two wheels is not material, but we prefer the wheel C' to be about one-fourth of the size of the wheel C.

D is a clutch-dog pivotally connected to an 55 arm d, extending from the gear C and engaging with the teeth of the ratchet-wheel B'. This dog is controlled or held in position by a spring d', which has one end secured to the arm d. A clutch-dog D' is pivotally connected to an arm d', extending from the gear-wheel C', and is held in engagement with the teeth of the wheel B² by means of a spring d'. The dogs D D' are designed to rotate the 60 shaft A alternately in opposite directions, as 65 will appear hereinafter.

E designates an operating-frame consisting of the two vertical rack-arms e e', which engage with the gear-wheels C C'. The frame E has an extension E', pivoted at its lower 70 end to a horizontal lever E², which is fulcrumed on a standard e², rising from the base of the machine. The fulcrum-point e³ of the lever E² is placed between the center and the outer end of the lever, so that a depression of 75 the outer end will result in a greater rise to the opposite end carrying the frame E.

To allow the frame E to move vertically in suitable guides, (not shown,) we provide an elongated opening e⁴ in the end of the lever 80 E², through which the pivot-pin E⁵ passes. An upstanding bar F has its lower end pivoted to the outer end of the lever E², and a foot-plate F' is rigidly attached to the upper end of this bar F. A link f is pivoted at one 85 end to the standard e² and at its opposite end to the bar F. This link serves to hold the bar F in an upright position, and by means of its pivotal connections allows a vertical movement to said bar.

The operation of the mechanism above described may be stated as follows: When pressure is brought to bear upon the plate F' by kicking or pushing with the foot or by striking the plate with a heavy mallet, the lever 95 E' is operated to raise the racks e e'. In this movement the rack e', through the agency of the gear C', the ratchet-wheel B², and the dog D', rotates the shaft A to return the dial to its normal or zero point, the dog D riding 100 over the teeth of the wheel B' without imparting action thereto. Upon relieving the

power the spring D², which is secured at one end to the base of the machine and at the other end to the lower end of the extension E', draws the racks back to their initial position, and the rack e rotates the shaft A and the dial, through the agency of the wheel C, the ratchet-wheel B', and the dog D, to bring a figure opposite the opening a², the dog D' riding harmlessly over its ratchet-wheel.

10 It is designed that the register or indicating number shall not be seen until a coin of proper value is inserted in the machine. We therefore provide a coin-operated shutter G, which normally closes the opening a² or is arranged between it and the disk or dial, as shown. The shutter G is attached to a lever g, which is here shown as pivoted to the hanger a and provided at its outer or free end with a coin-receptacle g'. A chute (not shown) guides a coin to this receptacle. G' is a counterbalanced latch pivoted on the upper portion of the rack e. When a coin of proper weight is inserted in the receptacle, the lever g is rocked downward, carrying the shutter out of the line of the opening a², and a lifting-pin g² on the lever g comes in contact with the upper side of the free end of the latch G', turning it on its pivot until the lifting-pin passes or slides beyond the latch, 25 when the latch, by means of its heavy or counterbalance end, resumes its normal position, with the pin g² bearing against its under side. The coin is then discharged and a stop g³, secured to the end of the rack e, prevents an upward movement of the free end of the latch G', so that the shutter G is held away from the opening until there is another upward movement of the rack-frame, when the pin g² is released and the lever allowed to rise, 30 closing the shutter. It will be observed that the movement of the pin g² is in the arc of a circle, so that it will not engage with the latch G' until a coin is inserted, as before stated.

Having described our invention, what we 45 claim is—

1. In a power-testing machine, the combi-

nation, with the main shaft, of a dial mounted on said shaft, ratchet-wheels mounted on said shaft, gear-wheels loosely mounted on the shaft, clutch-connections between the gear-wheels and adjacent ratchet-wheels, and racks 50 engaging the gear-wheels, substantially as specified.

2. In a power-testing machine, the combination, with the main shaft and a coin-operated shutter, of a dial mounted on the shaft, two ratchet-wheels rigidly mounted on the shaft, gear-wheels loosely mounted on the shaft, clutch-connections between the gear-wheels and adjacent ratchet-wheels, operating 55 the shaft in reverse directions, and a rack engaging with each of said gear-wheels, substantially as specified.

3. The combination, with the shutter, the shaft, the gear, and the clutch mechanism, 60 comprising ratchets thereon and the dial, of the racks, the fulcrumed lever having pivotal connection therewith, the upright pivoted to the outer end of the lever, and the plate thereon, substantially as specified. 70

4. In a coin-operated power-testing machine, the combination, with the rack and dial rotating mechanism, substantially such as described, engaging with the rack, of a counterbalanced latch pivoted on the rack, a shutter, 75 a pivoted lever extending from said shutter, a coin-receptacle on the free end of said lever, and a lifting-pin on the lever to engage the latch, substantially as specified.

5. In a coin-operated power-testing machine, 80 the combination, with dial-rotating mechanism substantially such as described, comprising a vertically-moving rack, of a shutter and a coin-receptacle having a lever portion detachably engaging with said rack in its 85 movement, substantially as specified.
